A. H. Evans & Co.

UNITED STATES PATENT OFFICE.

KNIGHT G. SMITH, OF PRINCETON, MISSOURI.

SPECULUM.

SPECIFICATION forming part of Letters Patent No. 367,248, dated July 26, 1887.

Application filed May 7, 1887. Serial No. 237,408. (No model.)

To all whom it may concern:

Be it known that I, KNIGHT G. SMITH, a citizen of the United States, residing at Princeton, in the county of Mercer and State of Missouri, have invented certain new and useful Improvements in Speculums, of which the following is a full, clear, and exact description, reference being had to the accompanying drawings, forming part of this specification, in

10 which—

Figure 1 represents a perspective view of a speculum embodying my improvements. Fig. 2 is a side view showing the upper valves raised. Fig. 3 is a rear view of Fig. 1. Fig. 15 4 is an enlarged sectional view on the line xx of Fig. 2.

My invention relates to the class of speculums, and it consists in the constructions and combinations of devices which I shall herein- 20 after fully describe and claim.

To enable others skilled in the art to which my invention appertains to make and use the same, I will now describe its construction and indicate how I carry out the same.

25 In the said drawings, A represents the lower section of the instrument, having at its rear the upwardly-extending sides B, united together at their tops by a cross-bar, C, and forming a frame within which the upper valves, 30 D, and their connections are suitably mounted, the bowl of said section A being made very deep, so as to increase the reflecting surface, and consequently the amount of light concentrated on the internal parts.

35 The valves D, which form the upper section of the instrument, are preferably two in number and have sockets a formed in their rear lower portions, the said sockets being adapted to receive conical eccentrics b, loosely mounted 40 on the inner ends of bolts c, whereby the valves are permitted to have a free movement on said eccentrics. By being thus mounted the valves are capable of unimpeded vertical movements, while set-screws e, passing through the lower 45 face of the valves and into the conical eccen- trics, serve as pivots upon which the valves turn, whereby the opening between their outer ends may be increased or diminished, as desired.

50 The valves D have upwardly-extending ears f, which are loosely connected with a bar or shaft, E, through the center of which is made

a perforation or slot adapted to receive the lower end of an adjusting-screw, F, the said screw being provided with collars g and h 55 above and below the shaft or bar, so that during the rotation of said screw the valves are drawn backward and swing upon the conical eccentrics to cause an elevation and spreading of their forward ends. The valves D are 60 secured on the shaft E by collars E' and screws in the ends of the shaft, so that the long valves can be removed and short ones put in their places.

Within the upwardly-extending sides B is 65 a suitable three-sided sliding frame, G, having depending arms k, through which the bolts c pass, the said bolts passing also through slots l in the sides of the extension B, and during the operation of an adjusting-screw, I, in 70 the top of said extensions the frame (which is connected with said screw) and the valves D are adjusted vertically to increase or diminish the dimensions of the instrument.

In the upper part of the frame G a rock- 75 shaft, J, is suitably mounted and has a threaded perforation adapted to engage the threaded adjusting-screw F, to effect the necessary vertical adjustments before noted.

From the above description it will be ob- 80 served that in operating my speculum the adjusting-screw F is moved to cause a spreading and elevation of the forward ends of the upper valves. If it be desired to increase the capacity of the device, the desired object is 85 obtained by turning the adjusting-screw I to cause the frame G and its attached valves to be vertically moved.

Having thus described my invention, what I claim as new, and desire to secure by Letters 90 Patent, is—

1. The lower section having the upwardly-extending slotted sides B, and the frame G within said sides, in combination with the eccentrically-moving valves D; the bar or shaft 95 connecting the upper ends of said valves, a rock-shaft, J, and the screw F, for elevating and spreading the forward ends of said valves, substantially as herein described.

2. The lower section having the upwardly-extending frame at its rear, and the upper valves, in combination with the frame G and the adjusting-screw I, substantially as herein described.

3. The lower section having upwardly extending slotted sides, the frame G within said sides, having the rock-shaft J, and the adjusting-screw I, in combination with the valves D, 5 the bolts c, passing through the slotted sides and frame, the conical eccentrics on said bolts and fitting sockets in the lower ends of the upper valves, the bar or shaft E, and the ad-

justing-screw F, engaging said bar and passing through a threaded opening on the rock-shaft, substantially as herein described.

KNIGHT G. SMITH.
